(57) **CLAIM**

The ornamental design for a pilsner glass, as shown and described.

DESCRIPTION

FIG. 1 is a perspective view of a pilsner glass showing my new design;

FIG. 2 is a front elevational view thereof;

FIG. 3 is a top plan view thereof;

FIG. 4 is a bottom plan view thereof;

FIG. 5 is a perspective view of a pilsner glass showing my new design;

FIG. 6 is a front elevational view thereof;

FIG. 7 is a top plan view thereof; and,

FIG. 8 is a bottom plan view thereof.

The broken lines in the drawings are included for the purpose of illustration and form no part of the claimed design.
